[57] CLAIM

The ornamental design for a fork or similar article of flatware, as shown and described.

DESCRIPTION

FIG. 1 is a top plan view of a fork or similar article of flatware showing my new design;

FIG. 2 is a right elevational view thereof, the left elevational view thereof being a mirror image of FIG. 2;

FIG. 3 is a bottom plan view thereof;

FIG. 4 is a front end view thereof; and

FIG. 5 is a rear end view thereof.

The essential feature of the design resides in the configuration of the handle in combination with the particular type of ornamentation incorporated therein.

FIG. 1

FIG. 2

FIG. 3

FIG. 4

FIG. 5
